COMBINED GEAR AND WINDING DRUM

John P. Templeman, Chicago, Ill.

Application August 20, 1942, Serial No. 455,465

8 Claims. (Cl. 254—149)

My invention relates to a combined gear and winding drum for use particularly in hand brakes for railway cars. It has for its primary object the provision of a winding drum in which a series of link-receiving pockets are provided around the periphery of the drum which receive the links of the chain uniformly in each winding operation, and in which each link is supported for substantially the whole of its length, thus affording the maximum support to the links during the chain winding operation and distributing the winding force throughout the links and also the drum.

Another object of my invention is the provision of a combined gear and winding drum in which the chain is wound on the drum with the links at an angle of approximately 45° to the vertical, so that each link is supported by the winding drum throughout the major portion of its length, thereby preventing any rolling of the chain and insuring uniformity of action throughout the entire operation of the winding mechanism.

In the provision of winding mechanisms for use in railway car brakes, various types of chain winding drums have been employed. In these hand brakes it is necessary to provide a winding surface of comparatively small circumference, and preferably concentric, so that the winding is uniform and of such a character that the chain being wound thereon will not roll, pile or slip, thereby resulting in serious accident and possibly death to a trainman. In the operation of railway brakes it is necessary to provide substantially the same power through the use of hand mechanism on the brake push rod as is exerted in the ordinary air brake. The force required of the hand brake mechanism is, therefore, around 4,000 pounds, so the hand brake mechanism must be capable of exerting great force, must be exceedingly strong and sturdy, and must be able to withstand a force much greater than this indicated amount, from a safety factor standpoint, so that the problem of winding a chain composed of comparatively short, heavy links around a drum of small circumference has been a major problem in securing proper operation of these hand brakes ever since power brakes were installed upon freight cars.

Various types of winding mechanisms have been employed, such as plain cylindrical surfaces, in which there is of necessity a slight twist in the chain as it is wound around the drum; drums provided with circumferential channels in the face thereof to receive the vertically positioned links of the chain and to support the al-

ternate links at their sides, usually by a circular surface of comparatively small diameter; and winding drums having a plurality of flat faces with channels in which the links are supported in the channel and at the sides. All of such winding mechanisms, however, have proven more or less unsatisfactory in service, due to a number of reasons, the chief one of which is the inability to support the links of the chain during the winding operation so that they do not bend in service, thereby ultimately resulting in fractures or broken links, which necessitate frequent inspection, and always with the possibility of the chain breaking during the application of a brake, thereby releasing the braking mechanism and throwing the trainman from the top of a car.

Another factor is exceedingly important in that the force applied to the hand wheel of the braking mechanism must be uniform, because trainmen are called upon to apply brakes under varying load conditions. For instance, they may have a single car which is empty and in another case a single car may have a heavy load therein. In other instances a string of cars may be coupled together and controlled by a single trainman, with the cars being all loaded or mixed with loads and empties, so that the application of brakes under these conditions must be under the control of the trainman at all times to secure the best results from the hand brakes. It is obvious, of course, that with a single empty car a braking force of lesser degree is needed than for a loaded car, and if the brakeman does not have within his power means for applying the power uniformly and regularly under all of the conditions named above, the brake is not suitable for installation in railway car service.

Another and further object of my invention is the provision of a combined gear and winding drum in which the winding surface is so arranged that the chain is wound thereon in a spiral manner, thus enabling a greater amount of chain to be wound thereon than would be possible if the winding surface were in a single plane, and affording a winding member having sufficient winding surface thereon to accommodate more than the usual length of chain required in installations of this character.

Another and further object of my invention is the provision of a combined gear and winding drum of small diameter for a heavy chain; in which the bending stresses are distributed over greater areas than what has been the practice heretofore where the stress areas of the links are

of small size, thereby eliminating point contact which causes the links to bend when subjected to strong force or stress.

These and other objects of my invention will be more fully and better understood by reference to the accompanying sheets of drawings, and in which—

Figure 1 is a wide perspective view of a combined gear and winding drum, with the wheel shown turned at approximately 240° from its normal unwound position;

Figure 2 is a view similar to Figure 1, except somewhat more narrow, showing the wheel at approximately 180° from its normal unwound position;

Figure 3 is a view similar to Figure 1, with the wheel shown turned to a position of approximately 250°;

Figure 4 is a perspective view of a combined gear and winding drum in its normal unwound position;

Figure 5 is a perspective view of the wheel and winding drum with the chain wound thereon in approximately the same wheel position as shown in Figure 2;

Figure 6 is a perspective view of the combined wheel and winding drum in wound up position; and

Figure 7 is a view with the chain in position on the winding drum in approximately the same position as the wheel shown in Figure 2.

Referring now particularly to the drawings and in which like reference characters refer to like parts throughout, a wheel 10 is shown having a rim portion 11 on the outer periphery of which gear teeth 12, 12 are formed. A flange 13 is provided integrally formed with the rim portion 11, and extends entirely around the wheel. A plurality of spaced spokes 14, 15, 16 and 17 are provided integrally formed with the rim portion 11 and flange 13 of the wheel, and extend inwardly therefrom to a hub 18. The hub 18 has a shaft opening 19 therein to receive a shaft upon which the wheel rotates in its normal operation, with the hub 18 extending through the gear wheel on each side thereof and forming at one side of the wheel a winding drum to receive the links of a chain as it is wound thereon. A chain receiving channel extends in a spiral direction about the hub 18, this channel being defined by the spokes and low webs of material on the side of the channel adjacent the wheel and by an outwardly extending flange 20 of variable height integrally formed with the hub 18 adjacent the outer end thereof. A web 21 is provided, integrally formed at one of its ends with the flange 13 and merges into the spoke 15 at its opposite end. A cam surface 22 is provided on the web member 21, which surface is angularly disposed to the vertical plane of the wheel, with its outer edge projecting outward slightly adjacent the vertical plane of the bottom edge, so that the links of a chain will slide thereon very easily and be forced outward, so that the chain begins to wind on the drum in a spiral direction.

A lug 23 is formed on the under side of the web 21 adjacent its point of attachment with the flange 13, with a flat surface 24 thereon and an opening therein to receive a pin 25. The pin 25 is mounted in a lug 26 integrally formed with the hub 18 and the spoke 14, the lug 26 having an opening 27 therein to receive the pin 25, and having a flat surface 28 parallel with the face 24 on the lug 23. The opening 27 is in alignment with a recess in the lug 23 to receive one end of

the pin 25, said pin being held in place by a cotter pin 29. The pin 25 is positioned at an angle of approximately 45° to the axis of the hub 18 and at an angle of approximately 45° to the vertical plane of the wheel, and extends through the first link of a chain so that the link is canted at an angle of approximately 45 both with respect to the plane of the wheel and to a plane parallel with the axis of the hub 18.

A chain, designated as a whole as 30, is provided, this particular length of chain comprising nine links, each link being approximately 3 inches long, 2 inches wide, and made of material $\frac{1}{8}$ of an inch in diameter, with the drum providing a winding surface which will take up the entire length of the chain amounting to approximately 16 inches.

Link A of the chain is secured to the wheel within the plane thereof by a pin 25 extending therethrough, and is supported by the faces 24 and 28 of the lugs 23 and 26, and also rests upon the hub 18 on the opposite side of the wheel from the winding surface. The link A is mounted at an angle of 45° to both the horizontal and vertical, so that as the chain is wound around the drum the other links maintain substantially the same 45° angle both with respect to the horizontal and vertical. Pockets are provided, as will be hereinafter described in detail, around the periphery of the hub 18, in such manner that the links are supported in an angular position along each of their sides for substantially the entire length of each link of the chain, thereby preventing the chain from bending under the tremendous force and stress which are placed upon the chain, and likewise preventing the chain from rolling or in any wise slipping as it is wound about the drum.

The link B of the chain 30, when in wound position, is supported by an inclined face 31 on the spoke 15 at one side and by surface 32 on the hub 18 which is inclined forwardly of the lug 26 and rib 33, and by the wall portion 34 of the flange 20 at its other side. The link B is guided into this position by the cam surface 22 during the initial winding of the chain 30 on the drum.

Link C is supported at one side by surface 35 on the hub 18 and low web 36 at the bases of the spokes 15 and 16, and by surface 37 on the inner face of the wall portion 38 forming a part of the flange 20 at its other side. Both the surfaces 35 and 37 are slightly dished in cross sectional contour and somewhat elliptical in a longitudinal direction, so that the link C is fitted into position and supported at each of its sides throughout the major portion of their length. The major portion of all bending stresses to which link C, and also all the other links of the chain normally used, is subjected, is not only transferred to the winding drum, but is distributed over supporting surfaces to such an extent that bending or breaking of the links is prevented, which is not the case where the bending stress is concentrated in a small area of both link and drum.

Link D at one side is supported by a surface 39 formed at one side of a fillet 40 of metal cast integral with the hub 18 and the spoke 16, and at its other side by a surface 41 on the inner face of a wall 42 forming a portion of the flange 20, the contour of the surfaces 39 and 41 being similar to the surfaces 35 and 37 hereinabove described.

Link E at one side is supported by a surface 43 on the inner side of a wall 44 forming a part of the flange 20, and at its other side the link

E is supported by a surface 45 formed by a low web 46 connecting the base of the spokes 16 and 17 and the surface of the hub 18, the surfaces of the recesses 43 and 45 conforming in surface contour to the similar recesses hereinbefore described.

Link F at one of its sides is supported by a surface 47 formed on a fillet 48 at the base of spoke 17 and hub 18, and at its opposite side by a surface 49 formed on the hub 18 and a wall 50 forming a part of the flange 20. The surface contour of the recesses 47 and 49 are similar to the surfaces 39 and 41, whereby the link F is supported throughout the major portion of its length at each of its sides while positioned at an angle of approximately 45° to the plane of the wheel and to the axis of its rotation.

Link G is supported at one side by a surface 51 formed by the hub 18 and a low web 52 connecting the spokes 14 and 17, and at its other side by a surface 53 formed in the wall 54 forming a portion of the flange 20, these surfaces 51 and 53 conforming in contour to the outer sides of the link G and being of sufficient length to support the link throughout the major portion of its length.

Link H is supported on one of its sides by a surface 55 formed in the rib 33, and at its opposite side by a surface 56 on the inner face of a wall portion 57 forming a part of the flange 20 extending around the end of the hub 18. In normal operation the link H will not be wound upon the drum, but in cases where, because of wear in the parts, additional take-up may be necessary, I provide supporting surfaces for it just the same as for the other links. In any event, the force on this link will be more in a straight line direction than a bending force and it is not necessary that the surface 55 support so much of the link. It will be noted also that this link H lies alongside link A and in substantial register with it, and the link I, which is secured to link H, is used merely as a connecting member to a brake rod, brake chain or other connecting member leading to other parts of the brake mechanisms.

In operation, the combined gear wheel and drum is mounted in a suitable housing, with the necessary gear and holding and release mechanism common to vertical power hand brakes, well known in the art, and which forms no part of the present invention. Assuming that the brake is placed in the usual position upon the end of a car, the gear wheel is mounted with the chain attaching pin 25 at the lower side and the chain hanging loosely therefrom, with its link I connected to a brake operating rod or to a chain leading to the brake operating mechanism secured to the bottom of the car. The gear wheel 10 rotates in a counterclockwise direction and in its normal operations the first links are wound on the drum with little resistance, the initial rotation serving merely to pull the slack out of the various brake operating parts. The link A is mounted upon the pin in substantial alignment with the center of the spiral winding surface, that is, at a slight angle to the plane of the wheel, so that the pull thereon is substantially in a straight line upon the pin 25. As the wheel rotates, the link B moves along on the cam surface 21 until it reaches the surfaces 31 and 32, where the link becomes fixed upon these surfaces. Upon the wheel being further rotated, each link is positioned automatically in proper position and supported by the surfaces

of the winding drum hereinabove described in detail, with each link being supported along each of its sides substantially for the length of the link. The contour of the engaged surfaces is such that there is no wedging of the links into these surfaces, but the links are fitted therein accurately so that there is no danger of the chain becoming fouled due to kinks therein, nor can the chain roll or slip in any way while it is being wound upon the drum.

Because of the fact that each winding is and must be exactly identical with the preceding winding, the pulling force exerted on the chain is uniform, enabling the trainman to make a steady and uniform application of the brake shoes to the wheels, and without any sudden release of the chain while the brakes are in partially applied position, causing the trainman to be pitched from his position on the car. Furthermore, because the links are firmly fixed in position about the drum, there is no bending or breaking of the links, and the winding mechanism will last indefinitely and without the necessity of constant inspection to see that the winding mechanism is in proper condition for serviceable operation.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of the appended claims.

35. What is claimed is:

1. Railway car brake chain winding means comprising in combination, a gear wheel having teeth around its outer periphery and an elongated hub portion having a winding surface thereon, and chain anchoring means on said wheel whereby the end link of a chain is secured to said gear wheel at an angle of approximately 45° to the vertical plane of the wheel, the said winding surface being composed of a series of pockets for receiving individual links of a chain, the said pockets being progressively positioned toward the end of the hub portion whereby a chain is wound on said surface in a spiral manner.

50. 2. A combined gear and winding drum having a hub portion forming a winding surface for a chain, and a pin for attachment of the end link of a chain to the gear wheel at an angular position both with respect to vertical and horizontal positions, the hub having a flange thereon having seating surfaces conforming in contour to one side of the link of a chain, and provided with seating surfaces on the side opposite the flange, all of said seating surfaces supporting one side of a link of a chain throughout a portion of the length of each link.

55. 3. A combined gear and winding drum comprising a toothed rim, a hub constituting a winding surface, spokes connecting the hub with the rim, the hub having a flange on its free end having link-receiving seats formed therein and having coating link-receiving seats formed in the bases of said spokes and in webs connecting the bases of some of said spokes, and chain attaching means on the said wheel.

60. 4. A combined gear and winding drum comprising a toothed rim, a hub constituting a winding surface, spokes connecting the hub with the rim, the hub having a flange on its free end having link-receiving seats formed therein and

having coating link-receiving seats formed in the bases of the said spokes and in webs connecting the bases of some of said spokes, and chain attaching means on the said wheel whereby a chain is secured to the said wheel with the links thereof at an angle of approximately 45° both to the plane of the wheel and to its axis of rotation.

5. A combined gear and winding drum comprising a toothed rim having a flange on the inner side thereof, a hub having a flange thereon adjacent one end thereof, spokes connecting the hub with the said toothed rim, a web having a lug at one of its ends integrally formed with the said flange and one of the spokes having a cam surface on one side thereof, one of said spokes having a lug formed at the base thereof opposite the lug on the said web, the said lugs having aligned openings therein and having parallel faces at an angle of approximately 45° to the plane of the wheel and to its axis of rotation whereby a chain is wound on the drum with the links thereof at angular positions, and a pin in said lugs, the flange on the hub having seats fashioned therein to receive and support one side of a link of a chain, with cooperating seats being formed at the base of the spokes to receive the links of the chain on the side opposite the said flange.

6. A combined gear and winding drum comprising a toothed rim having a flange on the inner side thereof, a hub having a flange thereon adjacent one end thereof, spokes connecting the hub with the said toothed rim, a web having a lug at one of the ends integrally formed with the said flange and one of the spokes having a cam surface on one side thereof, one of said spokes having a lug formed at the base thereof opposite the lug on the said web, the said lugs having aligned openings therein and having parallel faces at an angle of approximately 45° to the plane of the wheel and to its axis of rotation whereby a chain is wound on the drum with the links thereof at angular positions, and a pin in said lugs, the flange on the hub having seats fashioned therein to receive and support one side of a link of a chain, the bases of some of said spokes being connected with webs and some of

5 said spokes having fillets of metal at their bases integrally formed with the said spokes and the said hub, and having seats in the said fillets and said webs to receive one side of the links of a chain as it is wound upon the said drum.

7. Railway car brake chain winding means comprising in combination, a gear wheel having teeth around its outer periphery, a hub extending axially of the wheel, means connecting the hub with the toothed periphery, an outwardly spaced flange on said hub whereby a chain-receiving channel is provided between the said flange and the means connecting the hub with the toothed outer periphery of the gear wheel, the said flange having supporting surfaces for the links of the chain, the hub and the means connecting the hub with the toothed periphery adjacent the gear wheel having surfaces for the links formed therein complementary to the said surfaces formed in the flange, said surfaces supporting the links when the chain is wound about said hub in a manner whereby all of the links are disposed at an angle of approximately forty-five degrees with respect to the axis of rotation, and chain anchoring means on the said gear wheel for securing the end link of the chain thereto.

8. Railway car brake chain winding means comprising in combination, a gear wheel having teeth around its outer periphery, a hub extending axially of the wheel, means connecting the said hub with the toothed periphery, a flange around the outer end of the hub providing a chain-receiving channel between the said flange and the connecting means for the toothed rim and the hub, seats formed in the said flange at variable radial distances from the axis of rotation of the said wheel for receiving and supporting links of a chain, seats in said hub and said connecting means complementary to said first-mentioned seats for receiving and supporting the opposite side of the links of a chain at an angle of approximately 45° to the axis of rotation of the wheel, and chain anchoring means on the said gear wheel whereby the end link of a chain is anchored thereto.

JOHN P. TEMPLEMAN.
